UNITED STATES PATENT OFFICE.

ALBEN E. LUNDELL, OF NEW YORK, N. Y., ASSIGNOR TO WESTERN ELECTRIC COMPANY, INCORPORATED, OF NEW YORK, N. Y., A CORPORATION OF NEW YORK.

SEMI-AUTOMATIC TELEPHONE SYSTEM.

1,221,879.

Specification of Letters Patent. Patented Apr. 10, 1917.

Application filed June 24, 1916. Serial No. 105,582.

To all whom it may concern:

Be it known that I, ALBEN E. LUNDELL, a citizen of the United States, residing at New York, in the county of Bronx and

5 State of New York, have invented certain new and useful Improvements in Semi-Automatic Telephone Systems, of which the following is a full, clear, concise, and exact description.

10 The present invention relates to a novel circuit arrangement by which an operator in an extended trunking connection may signal a second operator, for example, a recording operator, not only initially to apprise her of the call but also after the first signal has been effaced by the act of the second operator in extending the call. Such signal may be employed for different purposes but the same is especially applicable

15 20 25

in cases where it becomes necessary to ring a called party a second time, as, for example, where he has hung up his receiver before the conversation was concluded.

20 The invention is particularly disclosed herein in a system of the semi-automatic or semi-mechanical class and in this case the operator who has the control of the sending mechanism by which the automatic switches are controlled, can come into the talking circuit at any time and as readily display the additional signal before the second operator.

25 30 35 The character of the invention will be more fully understood upon reference to the following detailed description taken in connection with the accompanying drawing and the scope of the invention will be particularly pointed out in the appended claims.

40 The drawing illustrates a circuit diagram of a system of the character referred to and which embodies the present invention.

45 In the particular system diagrammatically illustrated, the calling subscriber's line is extended by manually connecting it to a link-circuit and the latter has its circuit extended through an automatic switch to a second link-circuit which in turn is manually connected to a third link-circuit. From this point on, the circuit may be extended

50 55 55

in any desired way to the called subscriber. Two operators make these manual connections respectively. Inasmuch as the invention has to do with signaling from the first to the second operator, it is obvious that many different circuit arrangements may be

employed for extending the circuit of the calling line. The system of the present diagram is merely a typical embodiment of the invention.

50 In this diagram, a subscriber's substation M, having the usual equipment, is connected by a line L to a central office where the line terminates in the contacts on a jack J and is provided with the usual line relay LR, line lamp LL and cut-off relay CO. The 55 link-circuit L¹ extends from the plug P to the wipers of automatic switch S. A second link-circuit L² extends from bank contacts of the switch S to the contacts of a jack J¹. A plug P¹ co-operates with the jack 70 J¹ to extend the call through the link-circuit L³, and from this point on, as before stated, the circuit may be extended to the called line by any suitable circuits.

75 The operator who has control of the plug P has an operator's set OS and a sender SN. The second operator, who has control of the plug P', has an operator's set OS' which is associated with the link-circuit L³. The sender is used by the operator to control the operation of the automatic switch 80 S. The sender may be of any approved construction. A key-board sending mechanism of the type shown in Lundell Patent No. 1,168,319, dated Jan. 18, 1916, may be employed for this purpose.

85 The automatic switch S may also be of any approved type. It is here diagrammatically shown by a pair of wipers and associated bank contacts. The aforesaid 90 Lundell patent illustrates switches which might be employed in the circuit herein disclosed.

95 Certain of the circuit changes are brought about by a rotary switch, termed a sequence switch. In the drawing this switch is designated SS. The structure of the sequence switch includes a rotatable shaft having a series of disks of fiber or other insulating material secured thereto. On each side of 100 each insulating disk is a circular conducting plate which is cut away or skeletonized so as to provide any desired arrangement of contacts. The plates on the opposite sides of the disk are electrically united by securing 105 rivets. The rotatable disks are represented in the drawing in each instance by a long contact. A plurality of springs or brushes is provided for engagement with each pair of conducting disks and by means of these 110

- and by properly cutting away and arranging the plates on the insulating disk, any two or more brushes arranged for engagement therewith may be electrically united at any 5 stage of rotation of the shaft. The positions of the sequence switch at which the various springs or brushes are in engagement with the rotatable disk, are indicated by numerals placed adjacent to the several contacts respectively.
- 10 It may be here pointed out that in tracing a circuit through the contacts of a sequence switch, the designating numeral of the wiper will be used, followed by the number of the 15 position of the switch, the latter being in parentheses. Thus, with the switch in the seventh position and rotary contact 20 under consideration, the contact would be indicated by "20 (7)". The sequence switch SS 20 comprises rotatable contacts or wipers 20, 21, 22, 23, 24 and 25. Of these contacts all but 25 are closed in the positions indicated by the numerals adjacent to them. In the 25 case of contact 25, which is shown with a projection on its upper face, the circuit is closed at all points between the positions indicated by the numerals adjacent to it. In this switch the shaft 26 which carries the wiping or movable contacts, is driven from 30 a constantly rotating shaft 27 through magnetic clutch disks 28 and 29, which are brought into clutching engagement by the magnet SM.
- With this brief description of the principal portion of the diagram, we may pass on to a description of its operation when putting through a call from substation M and, in so doing, the circuit connections and other portions of the apparatus will be more 35 fully described. If the party at substation M initiate a call by removing his receiver from its hook, a circuit will be closed which will light line lamp LL. This circuit may be traced from the live pole of battery 30 through the left-hand winding of relay LR, normal contact 31 of cut-off relay CO, over the line through the substation and back through contact 32 of cut-off relay CO and the right-hand winding of relay LR, to ground. The resulting energization of 40 relay LR will light lamp LL by closing a circuit from the live pole of battery 33 through lamp LL, and closed contact 34 of relay LR, to ground. Upon observing the lighting of lamp LL, the first operator, namely, the one having control of plug P, will insert said plug into jack J and thereupon close a circuit for cut-off relay CO and control relay CR. This circuit may be traced from the 45 live pole of battery 35 through the winding of relay CO, jack and plug contacts 36, 37, and the winding of relay CR to ground. The energization of relay CO disconnects relay LR from the line and thereby de- 50 energizes it and causes the circuit of lamp

LL to be opened, with a resulting extinguishment of the signal. The energization of relay CR closes contact 38, but a circuit from battery 39 through supervisory lamp 40, closed contact 38 and normal contact 41 of supervisory relay 42, is prevented by reason of the latter relay having opened contact 41, by reason of the closing of a circuit over the subscriber's line. This circuit extends from the live pole of battery 43 through repeating coil winding 44, the winding of relay 42, plug and jack sleeve contacts, one limb of line L, through the substation, back over the other limb of the line, through jack and plug tip contacts and 55 repeating coil winding 45 to ground.

The energization of relay CR also closes contact 46 and thereby establishes a starting circuit for sequence switch SS which may be traced from the live pole of battery 47 through the winding of magnet SM, sequence contact 20 (1), conductor 48 and closed contact 46 to ground. The closing of this circuit causes magnet SM to bring the disks 28 and 29 into clutching engagement and thereby rotate the various movable contacts of the switch. As soon as the switch passes out of its first position, the circuit at sequence switch contact 20 (1) is interrupted but a maintaining circuit for 60 the magnet is established by way of contact 25 to ground, since the latter contact is closed at all positions between 1 and 7. As a result then, the sequence switch advances to the seventh position. In so doing, it 65 brings the operator's set OS into circuit with the strands of the link-circuit L¹ and the operator may obtain the calling party's order. The connections between the operator's set and the strand of the link-circuit are made at sequence switch contact 21 (6 to 8) and 22 (6 to 8). As soon as the order is received, the first operator sets up the number on the sender SN, or otherwise manipulates it according to its construction, and through sequence contacts 49 (11) and 50 (11) transmits impulses to the mechanism of the switch S to cause it to pick out a trunk or link-circuit L² to further extend the circuit of the calling line. The contacts 49 and 50 which are referred to as sequence switch contacts, are in systems of the type herein disclosed, the sequence contacts of another sequence switch, which is not shown, but for the purposes of this disclosure the same may be considered as moved by any suitable mechanism, or, if desired, by hand. In the operation of this mechanism, the contacts 49 and 50 are moved so as to complete the strands of the link-circuit L' as soon as 100 the sender has completed its operation.

As soon as the switch wipers 51, 52 engage the contacts 53, 54 of a selectable trunk or link-circuit L², trunk relay 55 is at once energized to light the lamp 56, which con-

stitutes the trunk signal for the second operator. The energizing circuit of trunk relay 55 extends from the live pole of battery 57 through the winding of relay 55, repeating coil winding 58, tip strand of link-circuit L^2 , switch contacts 53, 51, tip strand of link circuit L^1 , sequence switch contacts 50 (12 to 16), 24 (6 to 8), key 59, sequence switch contact 23 (6 to 8), and repeating coil winding 60 to ground. The circuit for trunk lamp 56 extends from the live pole of battery 61 through lamp 56, closed contact 62 of cut-off relay 63, and closed contact 64 of relay 55 to ground.

As soon as the second operator inserts plug P' into jack J' in response to the display of the trunk signal, the tip and sleeve strands of the link-circuit L^2 are connected to the corresponding strands of link-circuit L^3 and, by means of the key 65, the second operator may place her set OS' into talking relation with the first operator and receive the proper order for extending the call to the desired station. As soon as the plug P' is inserted into J' , a local circuit is closed from the live pole of battery 66 through protective resistance 67, plug and jack contacts 68, 69, and the winding of control relay 70 to ground. The closing of this circuit energizes relay 70 and at once establishes a connection to ground from the sleeve strand of link-circuit L^2 through the winding of coil 71 and closed contacts 72 and 73. By the establishment of this connection, current is suitably provided for transmission purposes. It may be here pointed out that the repeating coil winding 44 is mated with a winding 74. Likewise repeating coil winding 58 is mated with a winding 75 and the other windings of the latter coil are designated 76 and 77. A condenser 78 is interposed between windings 58 and 76.

When the first operator has completed her service in establishing the connection, she may free her set OS by operating the key LO, sometimes called the "listening-out" key, and thereby establish a starting circuit for magnet SM of sequence switch SS through sequence contact 20 (11) and closed contact LO to ground. This starting circuit will be followed by a maintaining circuit through sequence contact 25, which will insure an advance of the sequence switch to the eleventh position. In this position, the sequence switch contacts 21 and 22 will be open and sequence switch contact 23 (8 to 1) will be established, thereby cutting out key 59 which is in circuit in positions 6, 7 and 8 of the sequence switch.

It may be here pointed out that when the connection to ground through contacts 72, 73 of relay 70 is established, supervisory relay 78 is energized to show the presence of plug P' in jack J' of the associated trunk or link-circuit L^2 .

When both operators have performed their duties in establishing connection from substation M through the circuits L , L^1 , L^2 and L^3 , to the desired line, they are free to take care of other calls. If, at any time subsequent to this, the second operator is to be signaled, other means than the trunk lamp 56 are employed. When the control relay 70 is energized in response to the insertion of plug P' into jack J' , the trunk lamp 56 is extinguished. The energization of relay 70 closes a path for current through cut-off relay 63. This path may be traced from the live pole of battery 79 through the winding of relay 63, closed contacts 80, 81, and normal contact 82 to ground. The closing of this circuit at once establishes a locking circuit for relay 63 by way of contact 83—62 and closed contact 64 to ground. Contact 83 engages contact 62 so as to establish this locking circuit before the circuit of lamp 56 is broken. It will be noted that in this energized condition of relay 63, contact 82 is open.

If the called party should have hung up before the calling party had finished conversation, the latter, by operating his hook, could cause the winking of supervisory lamp 40 and thereby attract the attention of the first operator, who, by depressing her listening key L^1 , would establish a starting circuit for the magnet SM of sequence switch SS, by way of sequence contact 20 (11) and closed contact L^1 to ground. As a result, sequence switch SS will advance to its seventh, or listening in, position. This will enable the operator to learn from the calling party that he desires the called party to be rerung. In order to convey this information to the second operator, the first operator merely opens the contacts of key 59 which is included in the tip strand of the link-circuit L' in this position of sequence switch SS, and thereby opens the circuit of trunk relay 55. The resulting opening of contact 64 provides a new path for current from battery 79, which extends from the live pole of battery 79 through the winding of relay 63, closed contacts 80 and 81, and the winding of repeating relay 84 to ground. The latter is thereupon energized to connect battery 85 and protective resistance 86, which are in series, in bridge of the tip and sleeve strands of link-circuit L^2 . This is brought about by contacts 87 and 88 of relay 84. By placing battery 85 in bridge of the strands in this way, a trunk relay 89 is operated to display a second signal, herein shown as lamp 90. The energizing circuit for relay 89 may be traced from the live pole of battery 85 through resistance 86, closed contact 87, jack and plug tip contacts, winding of relay 89, plug and jack ring contacts, alternate contact 88 to ground. The energizing of relay 89 closes a local circuit for lamp 90 which may be traced from the live pole of battery

91 through lamp 90 and closed contact 92 of relay 89 to ground. The display of this signal to the second operator, who in certain instances may be the recording operator, informs her that the called-for party is to be rerung and she at once takes appropriate steps to bring about this result. As soon as the first operator has actuated key 59 to bring about this signaling of the second operator, she releases key 59 and closes key LO so as to bring her sequence switch SS out of the seventh or listening position into the eleventh position.

At the conclusion of conversation, the second operator withdraws plug P' from jack J' in response to any suitable supervisory indication and thereupon control relay 70 opens the branch to ground through coil 71 and causes a deenergization of supervisory relay 78, and, as a result of this changed condition, the first operator withdraws plug P from jack J and the various parts return to their normal condition in readiness for subsequent operations.

25 What is claimed is:

1. A telephone system comprising telephone lines, link-circuits for extending calling lines, automatic switches for connecting said link-circuits, operator's sending mechanism for controlling the operation of said automatic switches, a second operator's equipment associated with a link-circuit beyond said switch from the calling line, means for displaying a signal before the 30 second operator when the calling line circuit has been extended to her position, means whereby the second operator may efface said signal, and means whereby the first operator may subsequently display a 35 different signal before said second operator.

2. In a telephone system, telephone lines, a set of link-circuits for extending the circuits of said lines, a second set of link-circuits, automatic switches for connecting 45 a link-circuit of the first set to a link-circuit of the second set, operator's sending mechanism adapted to be placed in circuit with link-circuits of said first set to control the operation of said switches, a second operator's equipment available for connection to the link-circuits of said second set, means responsive to the operation of said switch to display a signal before said second operator, means under the second operator's 50 control for effacing said signal, and means under the first operator's control for displaying a further signal before said second operator whenever said first signal is effaced.

60 3. In a telephone system, telephone lines,

link-circuits for uniting said lines into conversational circuits, automatic switches for use in establishing such circuits, an operator's equipment associated with said link-circuits at one point, a second operator's equipment 65 associated with said link-circuits at another point, two signals before said second operator, means for displaying one of said signals in response to the operation of an automatic switch, means under the control 70 of the second operator for effacing said one signal, and means subsequently under the control of the first operator for displaying said other signal.

4. In a telephone system, trunk lines, 75 automatic switch mechanism for connecting corresponding strands of trunks to extend a circuit, a trunk relay, a battery and connections whereby said relay is energized over said extended trunk circuit, a signal 80 displayed in response to the energization of said relay, a cut-off relay for effacing said signal, means for locking up said cut-off relay through contacts of said trunk relay, a repeating relay, a second trunk relay, a 85 second signal operated by said second trunk relay, battery and connections for actuating said second trunk relay over another portion of the extended trunk circuit to display said second signal in response to the energization of said repeating relay, and circuit 90 connections whereby said repeating relay is energized in response to a deenergization of said first trunk relay.

5. In a telephone system, a trunk, a trunk 95 relay connected thereto, means for energizing said relay over said trunk, a trunk signal displayed in response to the energization of said trunk relay, a cut-off relay having a locking connection through contacts 100 of said trunk relay, a plug and a jack for connecting to said trunk, a control relay in circuit with a ring of said jack, battery connections to the mating contact of said plug whereby said control relay is energized upon 105 the connection of said plug and jack, a repeating relay, a path for current through said cut-off and repeating relays through contacts of said control relay, battery and connections adapted to be connected to said 110 jack tip and sleeve contacts by said repeating relay, a second trunk relay in bridge of the tip and sleeve contacts of said plug whereby the latter relay is energized in response to the energization of the former, and a second signal displayed in response to the 115 energization of said second trunk relay.

In witness whereof, I hereunto subscribe my name this 23rd day of June, A. D. 1916.

ALBEN E. LUNDELL.
